AIR CLEANER AND THE LIKE

Charles A. Winslow, Oakland, Calif., assignor to
Catherine B. Winslow, Oakland, Calif.

Application January 7, 1933, Serial No. 650,647

7 Claims. (Cl. 183—9)

This invention relates to air cleaners, and the principal object of the invention is the provision of new and improved means for removing impurities from air supplied to the crankcases and carburetors of internal combustion engines for use on automobiles, tractors and the like.

Another object of the invention is the provision of a new and improved air cleaner having new and improved means for removing foreign matter from the air immediately prior to its introduction into the engine by subjecting the same to an oil wetting operation prior to its passage through the filter material.

A further object of the invention is the provision of a new and improved air filter which is inexpensive to manufacture, easily installed, easily cleaned and which is efficient in use.

Other objects and advantages of the invention will appear from the following description taken in connection with the accompanying drawing, in which

The figure is a longitudinal, vertical section of the air filter with parts broken away; and

Referring now to the drawing, the reference character 5 designates generally the filter which comprises a container or casing 10 having the bottom wall 11 and the side wall 12. The bottom wall 11 forms with the lower portion of the side wall 12 an oil reservoir or sump 13. The bottom wall 11 is preferably depressed at its central portion and provided with a drain cock 9 for draining oil from said sump when it is necessary or desirable.

The upper end of the container 10 is provided with a closure 14 which may be hinged as at 15 to the side wall 12 of the container. The catch 16 opposite the hinge is adapted to hold the closure 14 in lowered position. The closure is provided with a downwardly extending inwardly offset flange member 17 which is adapted to engage within the interior of a wall 12 for forming a substantially air-tight joint.

The bottom wall 11 of the container is provided with an axial opening through which the tube or air conduit 21 extends. This conduit terminates at its upper end adjacent to but spaced from the closure 14 to provide a passage for air, as will presently appear.

Confined in the container 10 between the walls 12 and the conduit 21 is a mass of suitable filter material 22.

The filter material 22 is supported by a partition 23 in the lower portion of the container 10. This partition is provided with a central opening through which the conduit 21 extends

and is supported at its peripheral edge by the air deflectors 24 punched inwardly from the wall 12 of the container. An upper partition 25 in the container 10 is adapted to constitute the upper confining wall for the filter material. This partition is provided with a central opening 26 through which the conduit 21 extends. The peripheral edge of the upper partition 25 is secured to the wall 12 in any suitable manner as by being seated in the bead 27. The partitions 23 and 25 are of foraminous material whereby air may readily pass through the same.

It is desirable that the air upon first entering the casing or container 10 shall first be subjected to an oil wetting process whereby the greater portion of the dust and foreign matter will be deposited before the air passes into the filter material. Any suitable means may be provided for this purpose.

In the form of construction shown, the louvres 20 24, which are formed by making curved slots in the side wall 12 of the container and bending the tongues or tabs inwardly at an obtuse angle, form means for deflecting air, entering the openings 28 beneath the same, down onto the oil 25 contained in the sump 13.

These louvres or deflectors 24 extend downwardly and inwardly so that the air entering the ports 28 beneath these louvres is directed downwardly onto the oil contained in the sump 13. The contacting of the dust laden air with the oil will wet the dust and other foreign matter contained in the air, thereby causing it to be deposited in the sump 13 before it enters the filter material.

If desired, a conduit 29 may be secured in the upper portion of the casing or container 10 above the filter material. When it is desired to employ the device for cleaning air supplied to a carburetor, the conduit 21 is attached to the intake 40 passage of the carburetor. The conduit 29 may then be dispensed with or the same may be placed in communication with the crankcase above the oil level for removing gasoline vapors and the like from the crankcase. When the conduit 29 is thus used, the breather pipe is preferably provided with an air filter. If the conduit 21 is attached to the breather pipe of an internal combustion engine, then conduit 29 may be placed in communication with the intake manifold of the engine for removing the gasoline vapors from the crankcase. If desired, a valve may be provided in the conduit 29 for controlling the flow of gasoline vapor through the same. In ac-

tual practice the diameter of the conduit 29 is comparatively small.

In farm tractors and the like, it is common practice to provide the air intake of the carburetor with a vertical conduit extending above the tractor in order that the air supplied may be as free as possible from dust.

When used on tractors having this arrangement, the conduit 21 may be telescoped in the upper 10 end of this intake conduit so that the air may be cleaned before it is supplied to the carburetor.

When the device is used in this manner, conduit 29 may be dispensed with altogether or it may be placed in communication with the upper 15 portion of the crankcase for removing gasoline vapors and the like therefrom.

In the operation of the device, air will be drawn through ports 28 and will be deflected by the louvres 24 onto the surface of the oil contained 20 in the sump 13 and from thence the air will make a sharp turn upwardly and pass through the filter material which is kept in an oily condition where the final particles of dust are removed from the air. The air will then pass on upwardly into 25 the upper end of the conduit 21 and from the conduit 21 downwardly into the carburetor. The sharp turn in the movement of the air after it has been deflected downwardly onto the oil in the sump will also cause the coarser particles of 30 foreign matter to separate from the air by its inertia.

The air cleaner may be removed from time to time and dipped in kerosene or gasoline for cleaning the dirt from the filter material. Oil is supplied to the filter material by the air carrying 35 particles from the sump and also from oil mist carried by the air from the crankcase. If desired, oil may also be supplied from time to time by first raising the lid and pouring the oil onto the space around the conduit 21 above the material. The 40 excess will collect in the sump 13 and run out at the openings 28 when the oil level in the sump rises high enough.

The structure shown in the drawing is disclosed 45 in my Patent No. 1,888,813, dated November 22, 1932.

It is thought from the foregoing taken in connection with the accompanying drawings that the construction and operation of my device will be 50 apparent to those skilled in the art, and that changes in size, shape, proportion and details of construction may be made without departing from the spirit and scope of the appended claims.

What I claim is:

- 55 1. An air filter comprising a cylindrical casing having an oil sump in the lower portion thereof, a conduit extending axially into said casing through the bottom wall thereof, a closure for the upper end of said casing, said closure normally spaced above the upper end of said conduit, filter material extending about said conduit in spaced relation to the bottom of said casing, said casing having a plurality of openings in the side wall below said filter material and above said sump and means for directing air entering said casing 60 through said openings downward into said sump.
- 65 2. An air filter comprising a casing having an oil sump in its lower end, a movable closure for said casing, a tubular conduit extending axially upwardly into said casing and terminating short of the upper end thereof, filter material extend-

ing around the intermediate portion of said conduit, a foraminous partition for conducting air through said casing and for supporting said material above said sump and spaced therefrom, louvres for supporting said partition and for deflecting air entering said casing inwardly and downwardly into said sump preparatory to its passage through said filter material. 5

3. An air filter comprising a casing having a reservoir for oil in its lower portion, said casing 10 having a series of openings extending around its lower portion, filter material in said casing, means for supporting said material above the plane of said openings a conduit for conducting filtered air from said casing and means for deflecting air 15 entering said casing downward onto the surface of the oil in said reservoir for removing foreign matter therefrom preparatory to the passage of said air through the filter material.

4. An air filter comprising a casing having a 20 reservoir for containing oil in its lower portion, a tubular conduit extending into said casing, filter material within said casing extending unobstructed about said conduit, means for supporting said material above said reservoir, and means for 25 causing air entering said casing due to the engine suction to come into contact with the surface only of said oil and thereafter pass through said filter material, change its direction, and flow from said casing.

5. An air filter for internal combustion engines comprising a casing having an oil reservoir in its lower portion, a conduit extending into one end of said casing and terminating adjacent to the opposite end thereof, filter material extending 35 unobstructed about said conduit above said reservoir and spaced therefrom, and means including said conduit for conducting air through said casing and for causing air entering said casing to be directed downwardly onto the surface only of the 40 oil in said reservoir and to pass upwardly through said filter material for removing foreign matter from said air.

6. An air filter for internal combustion engines comprising a casing having an oil reservoir in its 45 lower portion, a tubular conduit extending into said casing, filter material within said casing and extending uninterruptedly around said conduit, means for supporting said material above and in spaced relation to said reservoir, and means in- 50 cluding said conduit for conducting air into and from said casing and for causing said air on entering said casing to be directed downwardly onto the surface only of the oil in said reservoir and to reverse its flow and to pass upwardly 55 through said filter material for removing foreign matter therefrom.

7. An air filter for internal combustion engines comprising a casing having an oil reservoir in its lower portion, a unitary filter element within 60 said casing above the normal level of the oil in said casing, means for supporting said element above said oil, passages leading into and from said casing for conducting air into said casing anterior of said filter element and for conducting 65 filtered air from said casing, and means above the oil level for deflecting air entering said casing onto the surface only of said oil prior to its passage through said filter element.
